To all whom it may concern:

Be it known that I, LOUIS L. Figure 1 is a front elevation of an ophthalmic mounting on an enlarged scale, showing my new design.

Figure 2 is a plan view of Figure 1.

The dominant feature of the design is the appearance, shape and contour of the rim and bridge parts shown in full lines.

I claim:

The ornamental design for an ophthalmic mounting as shown and described.

In testimony whereof, I affix my signature.
